UNITED STATES PATENT OFFICE.

GEORGE T. BAILEY, OF ST. PETERSBURG, FLORIDA.

COOLING DEVICE FOR BOTTLES AND PACKAGES.

1,023,116.

Specification of Letters Patent.

Patented Apr. 9, 1912.

Application filed September 20, 1910. Serial No. 582,841.

To all whom it may concern:

Be it known that I, GEORGE T. BAILEY, a citizen of the United States, residing in the city of St. Petersburg, in the State of Florida, have invented a new and useful Cooling Device for Bottles and Packages, of which the following is a specification.

My invention relates to cooling devices and consists in part of an ice retaining chamber having below it a water tank into which is fed by a serpentine passageway, by means of gravitation, cylindrical packages to be cooled therein and having a downward projection of one part of the ice chamber 15 to a point beneath the surface of the water preventing circulation of air from the lower part of the serpentine passageway; and some of the objects of my invention are:—1. To provide means of cooling by means of ice 20 in an ice chamber above the part and above the article to be cooled. 2. To provide means for automatically feeding the articles to be cooled to the water below the ice chamber. 3. To provide a trap to prevent the 25 circulation of air in the serpentine feed chamber or magazine. 4. To provide means for covering the articles to be cooled with a uniform casing to prevent them from becoming clogged in the serpentine chamber 30 or magazine. 5. To provide means of having the articles first taken from the cooling device to be submitted to the coldest water in the tank. 6. To provide means for releasing the package or carton in the front 35 of the train of cartons and for removing from the cooling tank and for releasing them singly as desired to be used. 7. To provide means for adding addition of sections to my cooling device so as to extend 40 the magazine containing the bottles, packages or cartons. 8. To provide means in the form of an expandible cylindrical carton for containing a bottle or other package so as to make a package or cylinder of uniform 45 sizes to be used in the serpentine passageway of the magazine. 9. To provide means of utilizing the cavities between the walls of the serpentine passageway and the walls of the case of the device to receive and to 50 cool such articles as fruit, meats or other perishable provisions. 10. To provide a non-conducting substance in an inclosing case to prevent the waste of the cooling influence of the ice by communication with 55 the atmosphere, etc. I attain these objects

by means of the construction illustrated in the accompanying drawings, in which:—

Figure 1, is a section of one edge of the cabinet of the device. Fig. 2, is a perspective of one of the extension sections alone. 60 Fig. 3, is a perspective of the cooling device with one of the extension sections thereon. Fig. 4, is a top view of Fig. 8. Fig. 5, is an end elevation of a bottle inclosed in the spring metal thimble shown collapsed in Fig. 6. Fig. 6, is an end elevation of the spring metal thimble shown in Fig. 5, as collapsed to its normal shape. 65 Fig. 7, is a side elevation of the spring metal thimble shown in Fig. 5, and in Fig. 6, and 70 containing a capped bottle. Fig. 8 is a right side elevation of the cooling device with one extension section thereon and showing the course of the thimbles shown in Figs. 5, 6, and 7. Fig. 9, is a front elevation of Fig. 8.

Similar figures refer to similar parts throughout the several views.

The cooling device 1, the serpentine passageway 9, with the trap formed by the 80 downward projection 15, into the water tank 4, and the extension section 2, constitute the principal framework of my device.

In the top part of the cooling device 1, is situated the ice chamber 3, in which is represented a lump of ice 8, with water extending up to the water line 16, in the bottom of the ice chamber 3. At the water line 16 is an orifice 17, which allows the drain from the melted ice to pass into the lower part of 85 the serpentine passageway or chute 9, until the said serpentine passageway or chute 9, and the water tank 4, are filled up level with the overflow pipe 5, so that any excess of water above the water line 16, will escape 90 through said overflow pipe 5.

To cool articles like bottle 11, they are submerged in the water in the serpentine passageway or chute 9, or in the water tank 4.

To prevent such articles, as bottles 11, 100 from cramping or clogging in the serpentine passageway or chute 9, I provide an elastic metal cylinder 10, which is shown in Fig. 6, collapsed in its normal shape and is shown expanding in Fig. 5, as when a bottle 11, is 105 forced into the spring metal thimble 10. These metal thimbles are made uniform for certain sizes of one of my cooling devices, but may be made longer or larger in either dimension to suit various packages or arti- 110

cles to be contained by them or to suit the various sizes or shapes of the serpentine passageway or chute for different numbers or sizes of my cooling devices. These spring metal thimbles when in their normal form are in the form of a cylinder with its parallel edges slit one inside of the other as shown in Fig. 6, and it may be opened or closed at the ends but for the purposes of retaining bottles or other tight cases impervious to water, they are open at both ends to facilitate the access of cold water to more readily cool the contents of the bottle as shown in Fig. 7.

15 The lower part 6, of the cooling device 1, I have designated a cooling receptacle and it is suitable for the retention and cooling of butter, meats, and other victuals, and is provided with a hinged door 7, for access to the cooling chamber 6, and for the purpose of shutting out the warm air from the same.

In Sheet 2, is represented Fig. 4, Fig. 8, and Fig. 9, drawn on the same uniform scale and containing the same parts. The ice chamber in Fig. 8, is represented as formed in part of the upper part of the cooling device 1, and the lower front part of the extension section 2, placed upon the device 1, and making an inclosed cover for the ice chamber 3. In the rear compartment 12, of the extension section 2, is an additional chamber for the retention or cooling of butter, meats and other food stuffs, which compartment 12, may be fitted or provided with other forms or compartments. In the upper front part of each extension section 2, is the compartment 26, which may be used to contain ice or other cooling substances or may be used to contain butter, meats and other victuals as desired. Each extension section 2, is provided at its top and bottom with arrangements to interlock with its mate above and below by means of the raised outer flange 13, at the top of each extension. The removable lid 14, is provided to cover the top-most extension Fig. 3. The rear wall 25 of each section of the serpentine passageway or chute 9, matches the rear wall at top and bottom of the connecting extension section and the front wall 24, of the serpentine passageway or chute 9, matches its corresponding front wall in each extension section above and below and thus makes the serpentine passageway or chute 9, continuous from the top of the uppermost extension to the bottom of the water tank 4.

60 The designating numeral 8, represents a lump of ice, in the ice chamber 3, and the same may be placed in the front upper compartment 26, of each extension section 2, if desired. However, the rule is to place ice in only the ice chamber 3, as it is not always necessary to cool the contents in the extension sections 2, 2, but the articles con-

tained in the spring metal thimbles 10, 10, should be cooled as they descend by gravitation to the water tank 4, preparatory to be taken out and used. As the water in the water tank 4, rises above the water line 16, 70 it escapes through the overflow pipe 5, thus preventing flooding of the ice chamber 3. It is designed that the water line 16, always extends above the downward projection or throat piece 15, of the ice chamber 3, thus forming a trap to prevent circulation of air from above the water line 16, of the water tank 4, up through the serpentine passageway or chute 9, or down through it thus preventing the warming of the water on the 80 articles contained in the serpentine passageway or chute 9, or in the cooling receptacles 6, 12, and 26, in Fig. 8.

The designating numeral 23 represents a sectional view of the edge of the metal wall 85 of the cooling device 1, and the extension sections 2, while 21, represents the wooden case or housing inclosing the whole cooling device excepting the top 14, of the uppermost extension section. Between the 90 wooden case 21, and the metal wall 23, is provided a filling comprising a coat 22 of cork or other non-conducting substances to prevent the transmission of caloric.

In each of the extension sections 2, 2, and 95 2, in the front thereof, is a continuous loop of the serpentine passageway or chute 9. The front wall 24, of this loop is permanently attached to the inside of the front wall 23 of the extension section 2, while each wall 100 of this metal wall 23 matches with its mate above and below.

The designating numeral 19, represents the intake of the serpentine passageway or chute while 18, represents the outlet at the 105 bottom of the serpentine passageway or chute 9, in each extension section 2.

The hole 17, in the bottom of the ice chamber 3, may be at or below the water line 16, as desired.

110 While in Fig. 7, is shown a bottle 11, clasped in the spring metal thimble 10, it is also understood that the spring metal thimble may be varied in its dimensions to contain packages of other forms and the 115 principal object of this metal thimble 10, is to form a uniform cylindrical package that will not clog in the serpentine passageway or chute 9, when moved by gravitation, but will roll or slide down the serpentine passageway or chute 9, to the bottom and front of the water tank 4, as shown in Fig. 8.

120 The cooling device 1, may be used alone, and in such case it will contain about 6, or 7, of the spring metal thimbles 10, and in 125 this case, it would be covered with the removable lid 14, shown on top of extension section 2, in section 3. After filling the serpentine passageway or chute in the cooling device 1, should it be desired to extend 130

the magazine for the spring metal thimbles 10, the operator will place upon the cooling device 1, one of the extension sections 2, either filled or empty. If placed upon the 5 same empty he can proceed to fill it by inserting thimbles containing the desired articles, as bottles 11, 11, into the intake 19, until it is filled when he may place the removable lid 14 thereon, or instead thereof 10 may place another extension section 2 thereon, and after filling the second section 2, may proceed as before, using as many extension sections as he may require to contain the quantity of spring metal thimbles 15 and their contents desired in the magazine at one time. The weight of the several packages contained in the thimbles 10, 10, will not cause an excessive pressure upon those below by reason of the additional 20 extension section 2, from the fact that the walls 24, and 25, tend to break the force of gravitation of the spring metal thimbles sustained by them from pressing excessively on the spring metal thimbles below each one 25 in succession. These said thimbles also protect the packages contained in them from pressure. When it is desired to remove the spring metal thimble, which is entirely exposed in the front of the water tank 4, the 30 operator lifts it from the water which act releases the next spring metal thimble pressing against it in line, in the serpentine passageway or chute 9; and the same is forced forward to the place previously occupied by 35 the one before it, now removed, by means of gravitation of itself and the pressure of its next mate in line behind it. The bottle 11, shown contained in the spring metal thimble 10, in Fig. 5, and Fig. 7, can be 40 pulled or pushed out at either end and used as usual.

As the coldest water in the tank 4, will be in the bottom of the tank, the article or articles contained in the spring metal thimbles 10, 10, will be gradually cooled from the first entrance into the water at the water line 16, in the serpentine passageway or chute 9, until they reach the coldest water in the tank at the bottom of the tank 4. 45 This form of cooling device is intended to be applicable to be connected with automatic devices for removing the spring metal thimbles 10, 10, and their contents from the water tank 4, such as the so called "coin in 50 the slot machines." This device is also intended to accommodate other forms of packages other than the spring metal thimbles 10, to be fed to the water cooling tank 4, through the serpentine passageway or chute 55 9, as desired.

The rear chamber 12, of the extension section 2, as well as the cooling receptacle 6, may be fitted with shells or compartments to contain or cool various victuals desired 60 to be placed therein.

I am aware that prior to my application, cooling devices have been used provided with an ice chamber above the cooling chamber, I therefore, do not claim such a combination broadly.

I claim:

1. In a cooling apparatus for bottles and packages, a suitable case, an inclined chute extending from the top of said case near its rear end to the front end of the case near 70 its bottom, an ice chamber in said case above the said inclined chute, a drain from said ice chamber to said chute, a downward projecting throat piece 15 at the front end of said ice chamber into the lower end of said chute, and a lid or cover for said ice chamber, all in combination with a plurality of cylindrical bottle or package cases provided to roll in said chute, substantially as set forth.

2. In a cooling apparatus for bottles and packages, a thimble made of a sheet of spring metal bent into the form of a hollow cylinder so that one longitudinal edge will over lap its opposite edge a distance approximating to the normal diameter of the respective cylinder, and provided to inclose a bottle or other package, in combination with a chute in which it is provided to roll downwardly, substantially as set forth, and for 95 the uses specified.

3. In a cooling apparatus for bottles and packages, a rectangular case, an inclined chute within said case, an ice chamber within said case and above said chute, an opening in 100 the top of said case above the lower end of said chute adapted to admit the human hand, a drain orifice in said ice chamber connecting with said chute, an overflow pipe in said case and above the lower end of the top wall or roof of said chute, and below the top of said opening, a downward projection 15, at the front end of said ice chamber and extending below the level of said overflow pipe, an opening in the upper end of said 105 chute to the top of said case, all substantially as set forth.

4. In a cooling apparatus for bottles and packages an extension section adapted to be placed upon the said cooling apparatus and having within it a serpentine shaped chute used as a magazine to receive and deliver packages of uniform shape and size, to the magazine in said cooling apparatus substantially as set forth.

5. In a cooling appliance for bottles or packages a suitable case, an inclined chute extending from the top of said case near its rear end to the front end of said case near 115 its bottom, an ice chamber in said chute, and a lid or cover for said chamber, an extension section 2, upon said cooling appliance and having within it a serpentine shaped chute used as a magazine to receive and deliver packages, all substantially as set forth.

6. A cooling appliance for bottles and packages comprising a rectangular case, an inclined chute, within said case, an ice chamber upon said chute, and within said case, an opening in the top of said case above the lower end of said chute large enough to admit the human hand, a drain orifice in the floor of said ice chamber connecting with said chute, an overflow outlet in front of said case and above the lower end of said chute and below the top of said opening, a downward watertight projection or throat 15, at the front end of said ice chamber and extending below the said outlet and the water line in said chute, an opening in the upper end of said chute to the top of said case, substantially as set forth and for the purposes specified.
7. In a cooling appliance for bottles and packages, the combination of a suitable rectangular case, an inclined chute within said case adapted to contain packages, an ice chamber above said chute and within said case adapted to contain ice, an accessible opening in the top of the front end of said case above the lower end of the said chute, and large enough to admit access of the human hand and to admit the extraction of said packages, a drain orifice in said ice chamber connecting with said chute, an overflow pipe in the front of the said case and above the lower end of said chute and below the top of said opening, a downward watertight projection or throat at the front end of said ice chamber and extending below the level of said overflow pipe and clear across said chute, an opening in the upper end of said chute to the top of said case, an extension section upon said cooling appliance and having within it a serpentine shaped chute

used as a magazine to receive and deliver packages to the said inclined chute below it, substantially as set forth.

8. In a cooling appliance for bottles and packages, the combination of a suitable rectangular case, an inclined chute within said case, an ice chamber above said chute and within said case, an opening in the top of said case above the lower end of said chute large enough to admit access of the human hand, a drain orifice in said ice chamber connecting with said chute, an overflow pipe in the front of said case and above the lower end of said chute and below the top of said opening, a downward projection or throat 55 piece at the front end of said ice chamber and extending below the level of said drain pipe, an opening in the upper end of said chute to the top of said case, an extension section provided upon the said cooling appliance and having within it a serpentine shaped chute adapted to be used as a magazine to receive and deliver packages of uniform shape and size, all substantially as set forth, and for the uses specified.

9. In a cooling apparatus for bottles and packages, the combination of a suitable case, an inclined chute extending from the top of said case near its rear end to the front end of the case near its bottom, in combination with a plurality of thimbles made of spring metal bent into the form of a hollow cylinder so that one longitudinal edge will overlap its opposite edge and provided to inclose a bottle or other package, substantially as set forth and for uses as specified.

GEORGE T. BAILEY.
